UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

BANK.

1,276,664.

Specification of Letters Patent. Patented Aug. 20, 1918.

Application filed October 24, 1916. Serial No. 127,350.

To all whom it may concern:

Be it known that I, JOSEPH KOMOROUS, a citizen of the United States, residing at Chicago, in the county of Cook and State of Illinois, have invented a new and useful Improvement in Banks, of which the following is a specification.

My invention relates more particularly to improvements in savings banks of the small, portable type and preferably adapted to be carried about in a person's pocket and into which coins may be readily inserted, and be withdrawable therefrom only upon opening the bank through the medium of a tool specially designed for this purpose, this type of bank being commonly employed by savings-bank institutions for distribution among its customers.

One of my objects is to provide a novel and simple construction of bank wherein the difficulties in opening the bank, by one not possessing the proper tool, shall be sufficiently great as to render it practically impossible to open the bank unless the proper tool is used: Another object is to provide means whereby the removable cover of the bank, which is removed to discharge the coins therefrom, may be locked in position on the cover without the use of a tool; and other objects are to provide improved guard-means for the coin-slot, to provide for the securing of the celluloid-covered disk to a disk coöperating therewith to prevent rotation of the covered disk independently of the other disk when grasped by the operator and turned in the course of either assembling or disassembling the parts, and to provide for a novel form of connection in a container between an end thereof and the adjacent edge of an annular side-forming member.

Referring to the accompanying drawings:

Figure 1 is a perspective view of a bank constructed in accordance with my invention. Fig. 2 is a top view of the bank with the cover removed. Fig. 3 is a face view of the inside of the cover. Fig. 4 is a section taken at the line 4 on Fig. 6 and viewed in the direction of the arrow, showing the cover locked in place. Fig. 5 is a view like Fig. 4, but showing one-half only of the bank, with a tool inserted therein for releasing the lock holding the cover in place, the tool being shown in the position it assumes

when the parts controlled thereby are released. Fig. 6 is a section taken at the line 6 on Fig. 4 and viewed in the direction of the arrow. Fig. 7 is a fragmentary view taken at the line 7 on Fig. 4 and viewed in the direction of the arrow. Fig. 8 is a detailed view in elevation of the coin-guard and the plate which with the wall of the bank, forms a housing for the guard, these parts being shown disassembled from the other parts of the bank. Fig. 9 is a view like Fig. 3 of a part of the construction therein shown, a portion thereof being shown in section to disclose a detail of the manner of engaging the celluloid-covered disk with the disk coöperating therewith. Fig. 10 is a fragmentary face view of a disk forming a part of the bank structure. Fig. 11 is a view in side elevation of the annular member forming the side-wall of the bank and which is connected with the disk of Fig. 10; and Fig. 12, a sectional view showing the manner of securing together the parts shown in Figs. 10 and 11.

The bank, generally stated, which in the construction shown is circular, consists of a body-section 20 and a cover-section 21, these parts being relatively rotatable, and means hereinafter described for releasably locking the cover-section 21, against removal, on the body-section 20. By preference, the body-section 20 is formed of a circular bottom plate or disk 22 provided about its outer edge with teeth 23; an annular member, or band, 24 provided about its lower edge with teeth 25 which mesh with the teeth 23 on the disk 22 and are bent over to overlap the bottom surface of the disk 22 as illustrated in Figs. 7 and 12; and a cover-disk formed of a disk proper 26 of relatively stiff material, as for example sheet-metal and having a continuous flange 27 with a covering 28 of celluloid crimped about the flange 27, the cover-disk being secured to the band 24 and disk 22 united as stated, by the flanged portion of the cover-disk which is crimped in placed about the lower edge of the band 24 which, by preference, is outwardly flared as shown. The annular member, or band, 24 contains a coin-slot 29 and is formed at its upper edge with an inwardly-projecting continuous flange 30 having a depending lip 31 along its extreme inner edge, said flange containing at intervals therein a series of arc-shaped notches 32 to 37 inclusive, all of

95

100

105

110

these notches in the particular construction illustrated, being unequally spaced, the distance between the notches 33 and 34, however, being only a slight distance greater than the distance between the notches 32 and 33.

The cover-section 21 is, in the particular construction illustrated, formed of two sheet-metal disks 38 and 39, the latter being covered with celluloid, as indicated at 40, and interlocking with the peripheral margin of the disk 38, by means of a flange 41 on the disk 39, the disk 38 being preferably downwardly offset at its peripheral portions from the disk 39. The cover 21 is provided on its underside with depending outwardly projecting angular lugs 42 to 47, inclusive, preferably stamped from the disk 38 and arranged in a circular series as represented in Fig. 3, these lugs being so disposed on the cover-section 21 that when the latter is applied to the body-portion 20 of the bank, to a certain position thereon, these lugs 42 to 47, inclusive, will register with the notches 32 to 37, inclusive, respectively, passing downwardly therethrough and extending below the plane of the lower edge of the lip 31 in which position the disk 38 rests at its lower surface upon the upper surface of the flange 30 at which flatwise-abutting surfaces the cover and body section are relatively rotatable on each other to cause the lugs to interlock with the flange 30, it being understood from the drawings that this is possible because the bases of the angular lugs 42 and 47, inclusive, lie within a circle of slightly less diameter than the diameter of the opening presented by the inner edge of the continuous flange 30. By preference the notch 33 is located centrally of the coin-slot 29 as illustrated in Fig. 4 and a struck-up portion 48 on the disk 38 in the same line radial of the center of this disk as the lug 43, serves as a means for indicating to the one assembling the cover with the body of the bank, the position to which the cover should be rotated for quickly properly positioning the latter to cause the lugs thereon to register with the coöperating notches 32 to 37, inclusive, respectively, in the body for interlocking these parts together.

It will be understood from the foregoing that it is necessary, before the cover 21 can be removed from the body-section to open the bank, that the cover occupy such a position on the body-section that its lugs 42 to 47, inclusive, register with the notches 32 to 37, inclusive, respectively, and to prevent the movement of the cover to a position wherein the lugs are in such position of registration, excepting by one using the proper tool, I provide the following described mechanism: The outer edges of the lugs 42 to 47, inclusive, are preferably arc-shaped to provide the curved surfaces 49,

with notches therebetween as represented at 50, these curved and notched portions co-operating with catches for releasably holding the cover against rotation on the body of the bank. While the distance between the lugs 42 and 43 is less than the distance between the lugs 43 and 44, the distance between the notches 50 in the lugs 42 and 43 is the same as the distance between the notches 50 in the lugs 43 and 44. These catches are shown in the form of spring-lugs 51 and 52, preferably formed as parts of a plate 53 of springy metal, these spring-lugs being formed by bending the ends 54 and 55 of the metal backwardly and inwardly to the position illustrated in Fig. 4, whereby the catches 51 and 52 are capable of being flexed. The plate 53, which preferably substantially snugly fits between the upper surface of the disk 22 and the under surface of the flange 30, is held against longitudinal movement by lugs 30^a struck downwardly from the flange 30, this plate containing a slot 56 which registers with the slot 29 and through which the coins are introduced into the interior of the bank. The catches 51 and 52 are spaced apart a distance equal to the distance between the notches 50 in the lugs 42 and 44 and the notch 50 in the lug 43, as illustrated in Fig. 4, these catches being preferably spaced an equal distance from the center of the notch 33.

After the operator applies the cover 21 to the body 20 of the bank to cause the lugs 42 to 47, inclusive, to register with the notches 32 to 37, inclusive, respectively, to lock the cover to the body he rotates the cover either to the left or to the right. Assuming that he rotates the cover to the left, viewing the bank in the position shown in Fig. 4, namely wherein the cover 21 is lowermost, the lugs 42 to 47, inclusive, will move out of registration with the said coöperating notches in the flange 30 and into registration with the imperforate portion of the flange 30 to a position in which the catches 51 and 52 extend into the notches 50 of the lugs 42 and 43, these catches in this movement riding upon the adjacent curved surfaces 49 of these lugs and springing into the notches 50 when the latter are moved into registration therewith. It will be understood from the foregoing that the cover 21 is thus locked against rotation on the body 20 of the bank and the lugs 42 to 47, inclusive, cannot be moved into registration with the respective notches 32 to 37, inclusive, until the catches 51 and 52 are withdrawn from the notches 50 into which they extend as described. A suitable tool is provided for withdrawing these catches to permit rotation of the cover 21 to the proper position for effecting its separation from the body. The tool for this purpose is represented in Fig. 5 and comprises

a pair of legs 57 pivotally connected together at 58 and provided at their outer ends with outwardly-turned extensions 59 having terminal-surfaces 60, and a shoe 61 mounted 5 on the pivot 58 and adapted to bear against the outer surface of the band-section 24 in the operation of springing the catches 51 and 52. To withdraw the catches 51 and 52 from the notches 50, the operator inserts the 10 outer end of the tool of Fig. 5 through the coin-slot 29 and the slot 56 to a position in which the surfaces 60 of the legs 57 bear flatwise against the inner surfaces of the free ends of the members 54 and 55, to one side 15 of the catches 51 and 52, the latter being located at the upper edges of these members (Fig. 7). The operator by grasping the opposite ends of the legs 57 and drawing them together spreads the ends thereof which are 20 disposed in the inside of the bank, and as the shoe 61 engages the outer surface of the band 24 and prevents the movement of the pivot 58 toward the center of the bank, the spreading of the ends of the legs 57 in the bank 25 while in engagement with the members 54 and 55, presses the latter outwardly in a direction to release the catches 51 and 52 from the notches 50 of the lugs 42 and 43.

It will be manifest from the foregoing 30 description that the cover 21 may be locked to the body of the bank by the mere act of applying the cover thereto in the proper position as stated, and thereupon rotating it in either direction, and while this manner of 35 locking the parts together is in accordance with the preferred embodiment of my invention, it will be understood that if desired the operator in applying the cover 21 to locked position on the body may withdraw the 40 catches 51 and 52 from the path of movement of the lugs 50, by using the tool shown in Fig. 5. In this connection it will be manifest that it is possible, that before the tool has been released to permit the catches 51 45 and 52 to extend into the path of the notches 50, the operator may have turned the cover 21 farther than the position in which the catches 51 and 52 register with the notches in the lugs 42 and 43 or 43 and 44, as the 50 case may be. Continued turning of the cover 21 under such conditions will cause one of the catches 51 or 52 to drop into one of the notches 50 in one of the lugs which will prevent the cover 21 from being turned until 55 this catch is released from the notch 50. Should one seeking to open the bank without the use of the proper tool, succeed in releasing from this notch 50 the catch which happens to extend into it, he may turn the 60 cover, but before the latter reaches a position in which it may be withdrawn from the body, both of the catches 51 and 52 will spring into the notches 50 in the lugs 42 and 43 or 43 and 44, as the case may be, depending upon the direction in which the cover is

turned, and thus make it necessary to release both of these catches 51 and 52 before the cover 21 can be rotated to the proper position for removal, and if the one seeking to remove the cover does not happen to 70 rotate the latter to a position in which both catches 51 and 52 enter notches 50, one of the catches 51 or 52 will enter a single notch and thus accordingly complicate and increase the difficulties of moving the cover 21 75 to proper position for opening.

The idea of providing two separately operative catches 51 and 52 which simultaneously are positioned in notches 50 in two of the locking lugs as stated, is to make 80 it practically impossible for one tampering with the bank, without using the proper tool, to open it, inasmuch as it is necessary in order that the bank be opened, to have both of the catches removed at the same 85 time. In order that the maximum difficulty in removing the catches from the notches 50, be presented, I preferably provide in the members 54 and 55, closely adjacent to the extremities thereof, holes 62 and preferably 90 inwardly offset the metal of the plate 53 at opposite ends of the slot 56 therein, as represented at 63, which thus prevents the flexing of the catches 51 and 52 by means of button-hooks, wires, knife blades, 95 etc. being inserted through the coin-slot.

The coin-slot of the bank in the construction illustrated is provided with a guard for preventing the removal of coins from the bank by withdrawing them through the 100 coin-slot. The form of coin-guard which is shown is designed more particularly for use where the coin-slot is of such proportions that it will permit of the introduction into the bank of coins of relatively large denominations as, for example, quarters, the bank as well being provided for receiving pennies, nickles and dimes, and the same principle may be applied to banks for receiving larger coins. The idea in this connection is to provide 105 a guard which shall be so constructed that it cannot be spread either to allow the smaller or larger coins to be withdrawn from the bank through the slot. The coin-guard as shown is made in sections 66 (Fig. 8), 110 each formed of a piece of spring-wire bent to present a pair of finger-sections 64 having diverging end-portions 65. These spring-wire sections are confined between the band 24 and the plate 53 to extend in opposite directions and are slightly spaced apart with the sections 64 of each pair thereof preferably in contact with and centrally disposed relative to the slot 29 as shown in Fig. 8, 115 these spring-wire sections 66 being held in place between shoulders 67 on the plate 53 formed by offsetting the latter (Fig. 4), and outwardly-struck lugs 68 on the plate 53. The wire from which the guard-device is formed is preferably round and it will be 120 125 130 135 140 145 150 155 160 165 170 175 180

readily understood from the foregoing that while the portions 64 of each of the separate sections 66 of the device will spread apart to permit a coin to be inserted into the bank, 5 the coins can not be withdrawn from the bank past the guard-device inasmuch as it would be necessary to spring apart the portions 64 of both sections of the guard-device simultaneously to permit the coins to pass 10 outwardly, even if it be a small coin, in view of the arrangement of the parts as shown and described, and such spreading of the coin-device would not be possible as the tool or tools by which the spreading would be 15 effected would obstruct the withdrawal of the coin.

In the constructing the cover-section 21 of the bank where the latter is formed, as is preferable, with a celluloid covered disk 39, 20 there is, under certain conditions, a possibility that the grip of the disk 39 as its flange-portion 41 thereon, against the disk 38 will not be sufficient to insure at all times the rotation of these parts as a unitary structure. To prevent any possibility of rotation 25 of the celluloid-covered disk 39 on the disk 38, I provide in the peripheral edge of the disk 38 preferably four, or more, notches, one of which is indicated at 69, into which 30 the celluloid forming the inturned portion of the covering 40 bulges and thus interlocks therewith in the operation of crimping the disk 39 to the disk 38 and holds these parts against relative rotation.

35 The feature of securing together the disk 22 and band 24 as hereinbefore stated, is desirable, especially where the bottom disk 26 is celluloid covered, inasmuch as the engagement between the band 24 and the disk 40 26 is celluloid to metal and might permit disengagement of these parts, the spilling of the contents of the bank under such condition being prevented by the rigid connection of the disk 22 with the band 24.

45 While I have illustrated and described a particular construction constituting what I now regard as the preferred form in which my invention may be provided, I do not wish to be understood as intending to limit 50 my invention to such construction as the same may be variously modified and altered without departing from the spirit of my invention, it being my intention to claim the invention as fully and completely as 55 the prior state of the art will permit.

What I claim as new and desire to secure by Letters Patent is:—

1. In a bank-structure, the combination of relatively rotatable receptacle-forming sections, one of said sections containing a 60 plurality of recesses, lugs on the other of said sections adapted to enter said recesses, one of said sections containing a coin-slot, and a plurality of spring locking means 65 operating, respectively, with said lugs and

adapted to automatically engage said lugs and releasably lock said sections against relative rotation to a position in which said lugs register with said recesses, upon the act of rotating said sections relative to each other to a position in which said lugs and recesses are out of registration, said locking means being releasable for permitting said sections to be relatively rotated to effect the registration of said lugs with said recesses 75 for permitting separation of said sections and in such releasing action requiring the action of force against both said locking means at the same time for holding both released against their spring tension. 80

2. In a bank structure, the combination of relatively rotatable receptacle-forming sections, one of said sections containing a plurality of recesses, pairs of spaced projections on the other of said sections adapted 85 to enter said recesses, one of said sections containing a coin-slot, and a plurality of spring locking means coöperating, respectively, with said sets of projections and adapted to automatically enter between the 90 projections of each pair thereof and releasably lock said sections against relative rotation to a position in which said sets of projections register with said recesses, upon the act of rotating said sections relative to 95 each other to a position in which said projections and recesses are out of registration, said locking means being releasable for permitting separation of said sections and in such releasing action requiring the action 100 of force against both said locking means at the same time for holding both released against their spring tension.

3. A tool for the purpose set forth comprising a pair of levers pivotally connected 105 together and each provided at one end with a laterally projecting extension, and a shoe device operatively connected with said levers and spaced from the said extension and projecting at opposite sides of said pivot. 110

4. A tool for the purpose set forth comprising a pair of levers pivotally connected together and each provided at one end with a laterally projecting extension, and a shoe device connected with the pivot connecting 115 said pair of levers together and spaced from the said extension and projecting at opposite sides of said pivot.

5. In a bank-structure, the combination with the wall thereof containing the coin-slot, of a coin-guard comprising pairs of resilient members which normally extend part-way across, and lengthwise of, the slot from toward its opposite ends and are movable in a plane substantially parallel with, 125 and substantially equidistant from, the wall containing said slot.

6. In a bank-structure, the combination with the wall thereof containing the coin-slot, of a coin-guard comprising discon- 130

nected pairs of resilient members which normally extend partway across the slot toward its opposite ends and are movable in a plane substantially parallel with, and substantially equidistant from, the wall containing said slot.

7. In a bank-structure, the combination of relatively rotatable receptacle-forming sections, one of which contains a plurality of recesses and the other of which carries a plurality of lugs adapted to enter said recesses and interlock with the one of said sections carrying the latter to prevent said sections from being separated, upon relatively rotating said sections, said lugs being provided with shouldered portions, and one of said sections containing a coin slot, and a member confined in said sections, said member containing a slot intermediate its ends disposed adjacent the said coin slot and having its ends formed of spring metal and extending toward said slot and provided with projections adapted to engage the shouldered portions of said lugs for the purpose set forth.

8. In a bank-structure, the combination of relatively rotatable receptacle-forming sections, one of said sections containing a recess, a lug on the other of said sections adapted to enter said recess and interlock with the section containing said recess, when said lug is moved to a position out of registration with said recess, said lug extending radially outward and containing a notch, and a spring-locking-device for releasably engaging said notch to lock said sections against relative rotation to a position in which said lug and recess register, said locking-device extending between the side wall of the bank-structure and the portion of said lug engaged by said locking-device.

9. In a bank-structure, the combination of relatively rotatable receptacle-forming sections, one of said sections containing a recess, a lug on the other of said sections adapted to enter said recess and interlock with the section containing said recess, when said lug is moved to a position out of registration with said recess, said lug extending

radially outward, and locking means carried by the one of said sections containing said recess and adapted in the relative rotation of said sections in either direction to interlock with said lug and prevent relative rotation of said sections to a position in which said lug and recess register, said locking means extending between the side wall of the bank-structure and the portion of said lug engaged by said locking means.

10. In a bank-structure, the combination of relatively rotatable receptacle-forming sections, one of said sections having an inwardly-projecting flange containing a recess, a lug on the other of said sections adapted to enter said recess and interlock with said flange when said lug is moved out of registration with said recess, said lug extending radially outward, and locking means carried by the one of said sections containing said recess and adapted in the relative rotation of said sections in either direction to interlock with said lug and prevent relative rotation of said sections to a position in which said lug and recess register, said locking means extending between the side wall of the bank-structure and the portion of the lug engaged by said locking means.

11. In a bank-structure, the combination of relatively rotatable receptacle-forming sections, one of said sections containing a recess, a lug on the other of said sections adapted to enter said recess and interlock with the section containing said recess, when said lug is moved to a position out of registration with said recess, said lug extending radially outward and containing a notch, with the portions of said lug at opposite sides of said notch inclined toward said notch, and a spring-locking device carried by the one of said sections containing said recess and adapted in the relative rotation of said sections in either direction to move against one of said inclines and interlock with said notch and prevent relative rotation of said sections to a position in which said lug and recess register.

JOSEPH KOMOROUS.
